(57) **CLAIM**

What is claimed is the ornamental design for a vented toilet, as shown and described.

DESCRIPTION

FIG. 1 is a front perspective view showing the vented toilet of Applicant's invention.

FIG. 2 is a front elevation of the vented toilet of Applicant's invention.

FIG. 3 is a right side elevation of the vented toilet of Applicant's invention.

FIG. 4 is a top view of the vented Toilet of Applicant's invention; and,

FIG. 5 is a bottom perspective of the vented toilet of Applicant's invention.

The broken line showing of toilet is included for the purpose of illustrating the vented toilet and forms no part of the claimed design.
